UNITED STATES PATENT OFFICE.

JOE M. MARTINEZ, OF DETROIT, MICHIGAN.

DESIGN FOR A CIGARETTE HOLDER.

Application filed February 27, 1926. Serial No. 16,691. Term of patent 14 years.

To all whom it may concern:

Be it known that I, JOE M. MARTINEZ, a subject of the King of Spain, residing at Detroit, in the county of Wayne and State of Michigan, have invented a new, original, and ornamental Design for a Cigarette Holder, of which the following is a specification, reference being had to the accompanying drawing, forming a part hereof, and in which,

Fig. 1 is a side elevation of the article, showing my new design.

Fig. 2 is a top plan view.

Fig. 3 is an end elevation.

Fig. 4 is a fragmentary sectional view taken on substantially line 4-4 of Fig. 2.

What I claim is:

The ornamental design for a cigarette holder as shown.

In testimony whereof I have signed the foregoing.

JOE M. MARTINEZ.
